UNITED STATES PATENT OFFICE.

GEORGE O. DRAPER, OF HOPEDALE, MASSACHUSETTS, ASSIGNOR TO THE DRAPER COMPANY, OF SAME PLACE AND PORTLAND, MAINE.

SPINDLE-BEARING.

SPECIFICATION forming part of Letters Patent No. 608,976, dated August 9, 1898.

Application filed May 22, 1897. Serial No. 637,706. (No model.)

To all whom it may concern:

Be it known that I, GEORGE O. DRAPER, of Hopedale, county of Worcester, State of Massachusetts, have invented an Improvement in 5 Spindle-Bearings, of which the following description, in connection with the accompanying drawings, is a specification, like letters on the drawings representing like parts.

Prior to this invention it has been customary to employ a step having at its upper end a screw-thread connected loosely with a screw-thread cut in the lower end of a bolster, and the lower end of the bolster and the step or a collar at its lower end have been connected with a spring, the step and part of the bolster being notched to receive in said notches loosely the ends of a spring, said spring preventing the rotation of the step in the supporting-case. This class of step has been used with a spindle having a tapered pintle fitting the tapered interior of the bolster, and at times the position of the step and bolster are relatively changed by or through said screw-thread to enable the fit between the pintle of the spindle and the interior of the bolster to be properly insured. In practice the step has been restrained from rotation by a pin or projection in the supporting-case. In applying this connected bolster and step to the supporting-case difficulty has been experienced in quickly causing the notched part of the step to find and properly embrace the pin of the supporting-case, which is to restrain its rotation, and so also in case it is desired to put a reverse twist into the yarn it is necessary to withdraw the bolster and step and change the spring and substitute for it one wound in a reverse manner. To obviate these difficulties, I have combined with the upper 40 end of the bolster and the upper end of the bolster-case a locking or restraining device which prevents the rotation of the bolster, leaving the step connected with the bolster only by the spring, the spring itself being the only means having any tendency whatever to restrain the rotation of the step with the spindle. As herein exhibited, the pin is carried by the bolster, and the slot is made in the bolster-case. This construction also brings the 45 wear of the spindle caused by the strain of

the band always on the same section of the bolster; but when worn the bolster may be given a quarter-turn and again locked in place, a suitable groove being made in the bolster to coöperate with the locking device 55 used.

Figure 1 of the drawings represents in section and elevation a spindle-bearing embodying my invention. Fig. 2 shows the step and the lower end of the bolster with which it is 60 connected.

The supporting-case A and the spindle B, having a sleeve-whirl B', are and may be all as usual. The upper end of the supporting-case is herein shown as provided with a groove a, 65 in which enters a pin or projection b, carried by the upper end of the bolster c, said bolster being notched at its lower end, as at c', and provided with an extension c², the bolster being surrounded between its ends, as herein shown, by fibrous or other suitable or usual packing, as c³. The chamber of the bolster-case receives a step d, the upper end of which, provided with a screw-thread, is screwed into the threaded lower end of the bolster, said 70 threads being made in the extension c² to form a support for the lower end of the spindle. The step is notched, as at d', and one end of the said spring e enters said notch, the other end of the said spring entering the notch c' of the 75 bolster.

With the bolster and step herein described they may be put together and pushed directly into the bore of the supporting-case, the pin or projection b of the bolster entering the 85 groove a at the top of the bolster-case, the step seating itself in the bottom of the opening of the bolster. Thereafter the bolster cannot rotate with the spindle, and when the bolster cannot rotate the step cannot rotate, 90 and the spring works just as well whether the twist put into the yarn by the spindle be a right or left twist, and when applying the step it readily finds its position in the bore of the bolster-case, and it does not have to be 95 turned about therein to find the usual pin.

The spring in this present invention merely serves the purpose of a spring or yielding lock between the bolster and step.

The bolster and step may be withdrawn, and 100

while the spring is compressed with the fingers the bolster may be turned on or with relation to the screw-threaded end of the step.

The threaded step and bolster are common to United States Patent No. 490,245, dated January 17, 1893.

Having fully described my invention, what I claim, and desire to secure by Letters Patent, is—

- 10 A bolster-case, a bolster located therein and tapered internally, said bolster being provided at its lower end with a screw-thread and a notch, means to restrain the free rotation of said bolster in said bolster-case yet permitting said bolster to be withdrawn and turned partially around to compensate when desired for wear of the bolster, combined with

a step having a screw-thread engaging loosely the screw-thread at the lower end of the bolster, and a spring interposed between a collar at the lower end of said step and the lower end of said bolster, said spring engaging at its opposite ends the said collar and said bolster, such construction enabling the same bolster and step to be used with a spindle turning either right or left, substantially as described.

In testimony whereof I have signed my name to this specification in the presence of two subscribing witnesses.

GEORGE O. DRAPER.
